(57) **CLAIM**

The ornamental design for a milling machine, as shown and described.

DESCRIPTION

FIG. 1 is a perspective view of a milling machine according to a new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a front right perspective view of the milling machine in an open state of use;

FIG. 9 is a front left perspective view thereof;

FIG. 10 is a left side elevational view thereof;

FIG. 11 is a right side elevational view thereof;

FIG. 12 is a front elevational view thereof;

FIG. 13 is a rear elevational view thereof;

FIG. 14 is a top plan view thereof; and,

FIG. 15 is a bottom plan view thereof.

The broken lines in the drawings depict portions of the milling machine that form no part of the claimed design.

1 Claim, 15 Drawing Sheets
